PROTECTIVE GARMENT WITH TROUGH MEANS

Corinne M. Murray, Yerba Buena Island, Calif.

Application July 5, 1949, Serial No. 102,997

4 Claims. (Cl. 2-48)

1

This invention relates to a garment for protecting the clothing of a person during the process of relieving a baby of accumulations of gas, a procedure that is now quite commonly termed "burping the baby" or causing it to belch.

One of the objects of the invention is the provision of a simple, certain and easily cleaned means for protecting the clothing of a person from being soiled during the so called procedure of relieving a baby of accumulations of gas in its stomach by the most approved method.

The most approved method at the present time for assisting a baby to eject gas from its stomach, and the method that has long been practiced by mothers and nurses, is for the mother or nurse to hold the baby against the front side of her shoulder with its face directed rearwardly over said shoulder, and to pat its back. The accumulated gas will be ejected from the baby's mouth, and usually moisture in one form or another accompanies the gas. Heretofore it has been customary to place a towel over the shoulder and this is intended to catch the moisture ejected from the baby's mouth, but the protection afforded by the towel is highly uncertain, and the towel absorbs such moisture as it receives requiring washing and drying of the towel. Also where a towel is used, the moisture ejected by the baby may fall on the rug or carpet or on the upholstery of furniture, according to where the "burping" process is conducted.

One of the objects of the present invention is the provision of a light protective garment that the mother or nurse may wear that will catch any moisture ejected from the mouth of a baby that is caused to belch or burp by the method above described, and which garment is of flexible waterproof material that may be rolled or folded without injury, and that can be thoroughly cleaned by a simple rinsing operation, and that is very quickly dried.

A still further object of the invention is the provision of a waterproof bolero that is quickly put on and as quickly removed, and which bolero is provided with a relatively shallow pocket extending across the back portion of the bolero from shoulder to shoulder in a position to catch the moisture ejected from the mouth of a baby that is held against the front side of one shoulder with its face directed rearwardly over said shoulder.

An added object of the invention is the provision of a waterproof horizontally elongated pocket adapted to extend from the outer end of the shoulder to the outer end of the other shoulder and across the back of a person at about

2

shoulder level for receiving the moisture ejected from the mouth of a baby held against the forward side of either shoulder of a person with its face directed rearwardly over either shoulder, and which object further includes means for releasably securing said pocket to the back portion of a garment adapted to be worn by said person.

Other objects and advantages will appear in the description and drawings.

10 In the drawings, Fig. 1 is a perspective view of the present invention as seen from the back of a person, and when on such person with a baby held in a position for relieving it of accumulation of gas in its stomach.

15 Fig. 2 is a rear elevational view of a bolero including the present invention.

Fig. 3 is an enlarged fragmentary sectional view showing the pocket, as seen from line 3-3 of Fig. 2.

20 Fig. 4 is an enlarged fragmentary view similar to that of Fig. 3, showing a modified form of the invention.

25 In detail, the invention comprises a jacket 1 or bolero, having a back portion 2 adapted to extend over the back of the wearer 3 (Fig. 1), particularly above the waist and across the shoulders.

The front of the bolero is connected over the shoulders with the back portion and arm openings provided for the arms of the wearer, with short sleeves 4 if desired.

30 The material of the bolero is preferably a waterproof, plastic material such as is commonly used for shower curtains, etc. Such material is light in weight and is non-absorbent, easily cleaned, relatively tough and may be heat sealed along seams. One suitable material is chlorinated rubber.

35 Secured to the back of the bolero 1 and at about the level of the shoulders, is a horizontally elongated relatively shallow pocket, generally designated 6, that may be of the same material as that of the bolero. Said pocket preferably extends from about the outer side of one shoulder to about the outer side of the other and has an inner side 7 and an outer side 8 and is closed at its ends.

40 The upper marginal portion of the outer side 8 may be folded outwardly one or more times on itself, thus forming a semi-flexible reinforcement 10 along said upper edge that tends to hold the upper side of the pocket open at all times, and if the pocket should be closed, it may be easily opened and will stay open due to the presence of 45 said thicker upper marginal portion.

The outer and inner sides of the pocket are integral at the bottom to provide a smooth curved bottom 11 that is seamless so that moisture can readily be cleaned from the pocket. The pocket may be made by merely folding a substantially rectangular blank on itself and heat sealing the ends together in positions to provide a normally widely open upper side.

The inner side 7 of the pocket may also be reinforced along its upper edge in a manner similar to the front side, and one of the elements 15 of conventional spring snaps may be secured to the outer surface of said inner side at spaced points therealong for releasable securement to the other element 16 of such snaps, the latter elements being secured at spaced points to the back portion of the bolero. These snaps are so arranged that the pocket will extend across said back portion at the desired level, which is at substantially the level of the shoulders. When in said position a baby 17 held against the front side of one shoulder of a person with its face directed rearwardly over said shoulder, will eject moisture from its mouth into the pocket, or at least none will contact the clothing of the wearer of the bolero, or will escape to the floor. Thus the baby may be safely handled and patted in the approved manner for relieving itself of accumulated gas on its stomach without damage to the clothing of the wearer or to any other article.

After the baby has been treated in the desired manner as above described, the bolero can be quickly removed and the pocket 6 removed from the bolero and washed or cleaned. The fact that the folds along the upper edges of the pocket are outward folds insures a clean, seamless surface along each of the upper edges of the pocket that are easily cleaned, which is not the case were a binding to go over said edges and to extend into the pocket.

If desired, the entire bolero can be easily and quickly washed. The bolero and pocket, being non absorbent, will dry quickly.

Fig. 4 shows a modified form of the invention in which the back portion 18 of the bolero itself forms the forward side of the pocket, and a single horizontally extending strip 19 may be heat sealed along its bottom and end edges to said back portion from the pocket.

The bolero and pocket being of flexible material of the same kind or of substantially the same kind, may be rolled or folded without injury to the material. Hence they may be packed into a small space for travellers, and the fact that they are non-moisture absorbent enables them to be quickly dried.

I claim:

1. A garment of the character described having a back portion adapted to extend across the back of a wearer in a position at about the level of the shoulders, means for securing said back portion to such wearer in said position, said portion including a pocket of waterproof material opening upwardly at a point behind a shoulder of said wearer for receiving moisture ejected from the mouth of a baby held against the forward side of said shoulder with its face directed

generally rearwardly over said shoulder, said pocket terminating at its ends on said back portion whereby said baby may be held close against said forward side of said shoulder and out of engagement with the walls of said pocket.

2. A garment of the character described having a back portion adapted to extend across the back of a wearer in a position at about the level of the shoulders and a front portion connected to said back portion and extending over the shoulders of said wearer for securing said back portion in said position, said back portion including a pocket of flexible waterproof material opening upwardly at a point behind a shoulder of said wearer and at about the upper level of said shoulder for receiving moisture ejected from the mouth of a baby held against the forward side of said shoulder with its face directed generally rearwardly over said shoulder, a semi-flexible reinforcing strip secured to said pocket along the upper edge thereof when said garment is being worn for holding the upper side of said pocket open, said pocket terminating at its ends on said back portion whereby said baby may be held close against said forward side of said shoulder and out of engagement with the walls of said pocket.

3. A garment of the character described having a back portion adapted to extend across the back of a wearer in a position at about the level of the shoulders, means for securing said back portion on such wearer in said position, a horizontally elongated pocket of flexible waterproof material having an open upper side and a horizontally extending bottom, said pocket being of a length to extend across said back portion substantially from the outer side of one shoulder of the wearer to the other, and means for securing said pocket to said back portion with its ends adjacent the outer sides of the shoulders of said wearer with the open upper side of said pocket positioned at about the upper level of said shoulders for receiving moisture ejected from the mouth of a baby held against the front side of a shoulder with its face directed rearwardly over said shoulder.

4. A garment of the character described having a back and a front portion adapted to respectively extend over the front and rear sides of the upper part of the body of a wearer, said back portion including an upwardly opening horizontally elongated pocket of waterproof material extending behind the shoulders with the upwardly opening side at about the upper level of the shoulders for receiving moisture ejected from the mouth of a baby held against the forward side of either of said shoulders.
